F. H. MERRICK.

TARGET TRAP.

APPLICATION FILED AUG. 7, 1908.

920,362.

Patented May 4, 1909.

UNITED STATES PATENT OFFICE.

FREDERICK H. MERRICK, OF HUNTINGTON, WEST VIRGINIA.

TARGET-TRAP.

No. 920,362.

Specification of Letters Patent.

Patented May 4, 1909.

Application filed August 7, 1908. Serial No. 447,465.

To all whom it may concern:

Be it known that I, FREDERICK H. MERRICK, citizen of the United States, residing at Huntington, in the county of Cabell and 5 State of West Virginia, have invented certain new and useful Improvements in Target-Traps, of which the following is a specification.

The present invention relates to certain 10 new and useful improvements in traps of that character which are employed for throwing disk targets, commonly known as "clay pigeons", and the object of the invention is the provision of a trap embodying a novel 15 construction whereby it can be readily set and released from the puller's stand.

The invention further contemplates a trap 20 which will be absolutely uniform in its action and will throw every target the same distance.

For a full understanding of the invention and the merits thereof and also to acquire a knowledge of the details of construction and the means for effecting the result, reference 25 is to be had to the following description and accompanying drawings, in which:

Figure 1 is a side elevation of a target trap embodying the invention, the throw arm being shown in a set position, Fig. 2 is a 30 sectional view on the line 2—2 of Fig. 1, looking in the direction of the arrow, Fig. 3 is an enlarged vertical longitudinal sectional view through the end of the frame, and Fig. 4 is a sectional view on the line 4—4 of Fig. 3.

35 Corresponding and like parts are referred to in the following description and indicated in all the views of the drawings by the same reference characters.

Referring to the drawing, the numeral 1 40 designates the base which is supported upon the legs 2 and is provided upon its upper surface with an annular race-way 3 receiving the balls 4. Pivotally mounted upon the base 1 is a plate 5 which is provided upon its 45 lower face with a race-way 6 also receiving the balls 4, the said plate resting upon the balls and being designed to rotate freely thereon. This plate carries the throwing mechanism and is designed to be held in an 50 adjusted position by means of set screws 7 engaging wings 7^a upon the base.

Projecting upwardly from the central portion of the plate 5 is a standard 8 and pivotally mounted upon this standard so as to 55 swing about a horizontal axis is a stock 9. The frame 10 which is disposed at substan-

tially right angles to the stock is secured at one end to the lower portion of the stock, the opposite end of the frame being returned upon itself at 10^a. With this construction 60 it will be obvious that by swinging the stock 9 about its pivotal connection with the standard the frame 10 may be moved either into a horizontal position or into a position at any desired angle to the horizontal. 65

Journaled between the frame 10 and the returned end thereof is a shaft 11, one end of the shaft projecting upwardly beyond the frame and having the throw arm 12 rigidly secured thereto at an intermediate point in 70 its length. One end of this throw arm is provided with the usual target carrier 13 while the opposite end is extended upwardly and connected to a main spring 14 which serves to swing the arm to project the target. In 75 the present instance one end of the main spring is connected to a rod 15 which passes through the upper end of the stock 9 and is capped by a nut 16. With this construction it will be obvious that by moving the nut in 80 and out upon the rod the main spring can be tightened or loosened as required.

Loose upon the shaft 11 between the frame 10 and the returned end thereof is a sprocket wheel 17 which is engaged by a chain 18, the 85 said chain passing between a pair of guide members 19 upon the frame, under a guide member 20 upon an arm 21 projecting from the base, and having the extremity thereof secured to a rod or pipe 22 leading to a lever 23 at the puller's stand. A coil spring 24 which is disposed under the sprocket wheel and has one end thereof secured to the sprocket wheel while the opposite end is secured to the frame tends to return the 90 sprocket wheel to its original position after the latter has been moved by pulling upon the chain or pull member 18. The upper face of the sprocket wheel has a dish formation and receives a disk 25 which is rigid with the 95 shaft 11, the periphery of the disk being formed with a notch 26 designed to engage a pawl 27 upon the sprocket wheel when the wheel is moved in one direction, the pawl slipping over the notch when the wheel is 100 moved in the opposite direction. A spring 28 bears against the inner end of the pawl and normally holds it yieldingly against the disk 25 while the outer end of the pawl is extended upwardly at 27^a and adapted to engage a trip arm 29 which serves to move the 105 pawl into an inoperative position when the

110

sprocket wheel has been turned a sufficient amount to set the throw arm.

By pulling upon the lever 23 tension is produced in the chain or pull member 18 and the sprocket wheel 17 which constitutes a resetting member is turned against the action of the coil spring 24. As the wheel is thus turned by the pull member the pawl 27 engages the notch 26 and locks the shaft 11 with the wheel so that the latter is turned and the throw arm 12 moved against the action of the main spring 14. When the throw arm has been moved to the set position it is engaged by a spring catch 30 upon the frame 10 and the upwardly extended end 27^a of the pawl then engages the trip arm 29 to move the pawl into an inoperative position and break the interlocking connection between the shaft and the sprocket wheel. The catch 30 is designed to be tripped by a chain or tension member 31 which is returned upon itself about a guide member 32 and has the extremity thereof secured to the pull member 18. The connection between the chain 31 and the pull member 18 is so adjusted that upon a continued movement of the pull member after the throw arm has been set and the interlocking connection between the wheel 17 and the shaft 11 broken, tension will be produced within the chain 31 and the catch 30 moved to release the throw arm. The target will then be projected in the usual manner and when the lever 23 is released the coil spring 24 will move the sprocket or resetting wheel 17 back to its original position. With this construction it will be obvious that by swinging the lever 23 at the puller's stand the throw arm can be automatically set and then released.

Having thus described the invention, what is claimed as new is:

1. In a target trap, the combination of a frame, a shaft journaled upon the frame, a throw arm rigid with the shaft, a spring for the throw arm, a catch for the throw arm, a resetting wheel loose upon the shaft, means for locking the resetting wheel with the shaft, means for turning the resetting wheel to move the throw arm against the action of the spring until it is engaged by the catch, and means for automatically releasing the resetting wheel from engagement with the shaft after the throw arm has been engaged by the catch.

2. In a target trap, the combination of a frame, a shaft journaled upon the frame, a throw arm rigid with the shaft, a spring for the throw arm, a catch for the throw arm, a disk rigid with the shaft, a resetting wheel loose upon the shaft, a pawl upon the resetting wheel for engaging the disk when the resetting wheel is turned to move the throw arm against the action of the spring, a trip upon the frame for releasing the pawl from engagement with the disk when the throw arm has been set, a pull member for turning the resetting wheel to set the throw arm, and an operative connection between the pull member and the catch.

3. In a target trap, the combination of a frame, a shaft journaled upon the frame, a throw arm rigid with the shaft, a spring for the throw arm, a catch for the throw arm, a resetting wheel loose upon the shaft, means for locking the resetting wheel with the shaft, a pull member for turning the resetting wheel to move the throw arm against the action of the spring until it is engaged by the catch, an operative connection between the pull member and the catch, means for releasing the resetting wheel from engagement with the shaft when the throw arm has been set, and a spring for turning the resetting wheel to its original position after it has been released.

4. In a target trap, the combination of a frame having one end thereof returned, a shaft journaled upon the frame and the returned end thereof, a throw arm rigid with the shaft, a disk rigid with the shaft, a resetting wheel loose upon the shaft, both the resetting wheel and the disk being located between the frame and the returned end thereof, a pawl upon the resetting wheel for engaging the disk to lock the two members together when the resetting wheel is turned in one direction, the said pawl being provided at its pivot end with an extension, means for turning the resetting wheel to set the throw arm, and a trip upon the frame for engaging the extension of the pawl for releasing the pawl from engagement with the disk when the throw arm has been set.

In testimony whereof I affix my signature in presence of two witnesses.

FREDERICK H. MERRICK. [L.S.]
